UNITED STATES PATENT OFFICE.

CHRISTIAN W. HINRICHES, OF ST. LOUIS, MISSOURI.

MEAT-CUTTING MACHINE.

SPECIFICATION forming part of Letters Patent No. 588,823, dated August 24, 1897.

Application filed October 12, 1896. Serial No. 608,640. (No model.)

To all whom it may concern:

Be it known that I, CHRISTIAN W. HINRICHES, of the city of St. Louis, State of Missouri, have invented certain new and useful 5 Improvements in Meat-Cutting Machines, of which the following is a full, clear, and exact description, reference being had to the accompanying drawings, forming a part hereof.

My invention relates to meat-cutting machines; and it consists in the novel construction, combination, and arrangement of parts hereinafter shown, described, and claimed.

Figure 1 is a top plan view of my improved meat-cutting machine, parts being broken away to more clearly illustrate the construction. Fig. 2 is a transverse vertical sectional view taken on the line 2 2 of Fig. 1. Fig. 3 is a side elevation of the left side of the machine, looking in the direction indicated by the arrow 3 in Fig. 1. Fig. 4 is a rear elevation of the machine, looking in the direction indicated by the arrow 4 in Fig. 3. Fig. 5 is a transverse sectional view taken approximately on the line 5 5 of Fig. 1 and looking in the direction indicated by the arrow, parts being broken away to economize space. Fig. 6 is a horizontal sectional view taken approximately on the line 6 6 of Fig. 5, parts being broken away to economize space. Fig. 7 is a horizontal sectional view taken approximately on the line 7 7 of Fig. 3. Fig. 8 is a vertical sectional view taken approximately on the lines 8 8 of Figs. 1 and 9, parts being broken away to economize space. Fig. 9 is a horizontal sectional view on the line 9 9 of Fig. 8, parts being broken away to economize space. Fig. 10 is a plan view of a portion of one of the knife-carrying shafts and an illustration of the method of attaching the knives 40 to the shaft. Fig. 11 is a transverse sectional view taken approximately on the line 11 11 of Fig. 10.

For convenience and precision in describing the machine I will designate the belt side of the machine or that side shown in elevation in Fig. 4 as the "rear." The side opposite the belt side I will designate the "front," and the right and left sides of the machine are designated as they would appear to a person 50 standing in front of the machine.

In the construction of my improved meat-

cutting machine I employ the base 20, which base is covered by the rigid base-plate 21. The base 20 consists of the rear piece 22, the front piece 23, and the side pieces 24 and 25, 55 connecting said rear and front pieces.

The rear piece 22 consists of the vertical corner-posts 26 and 27 and the horizontal bars 28 and 29, connecting said posts, and the horizontal bar 29 connects the upper ends of the 60 posts 26 and 27 and the horizontal bar 28 connects the central portions of said posts. The corners of the opening 30, which opening is formed by the horizontal bars 28 and 29 and the posts 26 and 27, are rounded, as indicated 65 by 31. The horizontal bar 29 is rectangular in cross-section and stands upon its edge, its vertical measurement being two or three times as great as its horizontal measurement, and the slot 32 is formed approximately in 70 the center of the upper edge of said horizontal bar. Projections 33 and 34 extend toward each other from the lower ends of the posts 26 and 27 and form feet for said posts.

The portions 35 of the rear piece 22 are segments of a circle upon their edges, and said circle corresponds substantially to the circle described by the portions 31. The horizontal bar 28 is in the form of an angle-bar in cross-section, the web 36 of the bar projecting in- 75 wardly in a horizontal plane and the web 37 extending downwardly with its outer face in alinement with the outer faces of the posts 26 and 27 and the horizontal bar 29. The web 36 and the bar 28 is cut enough shorter than 80 the horizontal bar 29 to allow the side pieces 24 and 25 to be inserted against the ends of said web 36, with their outer faces in alinement with the ends of the horizontal bar 29, as shown in Fig. 7.

A split bearing 38 rests upon the horizontal bar 28, and the lower part 39 of said bearing is formed integral with the upper face of the web 36 of the horizontal bar 28.

The construction of the front piece 23 is 95 identical with the construction of the rear piece 22, with the exception that the slot 32 is omitted and a slot 40 is formed near one end and from the upper face of the horizontal bar 29. The rear piece 22 and the front piece 100 23 are each cast integral, as described.

The left-hand side piece 24 consists of the

vertical posts 41 and 42 and the horizontal bars 43 and 44, connecting said posts. The horizontal bar 44 connects the upper ends of the posts 41 and 42 and the horizontal bar 43 5 connects the central portions of said posts. The horizontal bars 43 and 44 are rectangular in cross-section and their vertical measurements are two or three times as great as their horizontal measurements. The portions 10 of 45 of the side piece 24 are segments of a circle, formed by the junction of the horizontal bars with the vertical posts. The projections 46 and 47 extend toward each other from the lower ends of the posts 41 and 42 and form 15 feet for said posts. A horizontally-extending recess 48 is formed in the upper edge of the horizontal bar 44.

The right-hand side piece 25 is identical in construction with the side piece 24, except 20 that the recess 48 is omitted. The left-hand side piece 24 and the right-hand side piece 25 are each cast integral, as described, and the ends of said side pieces are inserted against the inner faces of the ends of the front and 25 rear pieces, with the ends of the webs 36 against the inner faces of said side pieces and the lag-screws 49 inserted through the ends of said side pieces and into the ends of said webs 36, as shown in Fig. 7.

30 The bearings 38 upon the rear piece 22 and the front piece 23 are in alinement with each other, and a shaft 50, carrying the worm 51, is placed in said bearings. The upper portions 52 of the bearings are held in position 35 and rigidly secured to the lower portions 39 of the bearings by means of the lag-screws 53, and oil-boxes 54 are attached to said upper portions 52 in the usual way. A collar 55 is placed upon the shaft 50, inside of the 40 bearings carried by the rear piece 22.

A belt-wheel 56 is rigidly mounted on the shaft 50 behind the rear piece 22 with its hub engaging the rear face of the bearing and holding said shaft from lateral movement. 45 A smaller belt-wheel 57 is rigidly fixed to the shaft 50 behind the belt-wheel 56, and a belt-wheel 57^a, similar in every respect to the belt-wheel 57, is loosely mounted behind said belt-wheel 57 and upon the shaft 50.

50 A spider 58 is placed inside of the frame formed by the rear piece 22, the front piece 23, and the side pieces 24 and 25, the ends of its arms being secured to the webs 36 of the horizontal bars 28 by means of the bolts 59. 55 The spider 58 consists of the circular portion 60, having a vertical bore through its center, and the arms 61, 62, 63, and 64 radiate from said circular portion to the corners of the frame. Said arms are T-shaped in cross-section 60 and are attached to the lower part of the circular portion 60 and extend slightly upwardly as they extend outwardly, as shown in Fig. 2. The spider 58 just described is cast integral. A horizontal bore 65 is formed in 65 the circular portion 60 and intersects the vertical bore in said portion, and a section of pipe 56 is screw-seated in said bore 65 and

extends outwardly and upwardly to a convenient position, and an oil-box 67 is attached to the upper end of said pipe. 70

The base of the machine, as described, is nearly square in plan view, and the base-plate 21 rests upon the upper edges of the horizontal bars 29 and 44. A short distance in front of the center of the base-plate 21 is 75 a circular portion 68, extending both above and below the body of the plate and having a vertical bore in vertical alinement with the bore in the circular portion 60. A shaft 69 is mounted with its lower end in the vertical 80 bore in the circular portion 60 and with its upper end projecting upwardly through the vertical bore in said circular portion 68. A worm-gear 70 is rigidly fixed to the shaft 69, above the lower bearing of said shaft and in 85 position to be driven by the worm 51. A collar 71 is mounted upon the shaft 69, below the upper bearing of said shaft. A horizontal bore 72 is formed from the side and upper end of the circular portion 68 and intersects the vertical bore in said circular portion, and a pipe 73 is screw-seated in said bore and extends outwardly from said circular portion above the plate 21 to a position near the edge of said plate and thence upwardly, and an oil-box 74 is attached to the upper end of said pipe. A pair of ears 75 extend downwardly from the lower face of the plate 21 and inside of the horizontal bar 29 of the left-hand side piece 24, and said 100 ears are secured to said horizontal bar by means of the bolts 76. A pair of ears 77 extend downwardly from the lower surface of the plate 21 and inside of the horizontal bar 29 of the right-hand side piece 25, and said ears are 105 secured to said horizontal bar by means of the bolts 78. A lug 79 extends downwardly from the lower face of the plate 21 and near the rear edge thereof, and a rectangular opening 80 is formed through said lug in horizontal 110 alinement with the recess 32, formed in the upper edge of the rear piece 22. A lug 81 extends downwardly from near the center of the base-plate 21, and a rectangular opening 82 is formed horizontally through said lug and 115 in alinement with the opening 80 and the recess 32, and a sliding bar 83 is mounted in said opening. A plate 84 is attached to the rear end of the sliding bar 83 and extends 120 downwardly upon the left side of said bar, and said plate has a horizontally-extending opening through its lower end through which the driving-belt operates, and the operation of said plate 84, by sliding the bar 83, shifts the driving-belt from the tight pulley 57 to the 125 loose pulley 57^a, and vice versa.

A circular lug 85 is formed upon the lower face of the plate 21 and a belt-shifting lever 86 is placed in the recess 48 and below said lug and is pivotally connected to said lug by 130 means of the lag-screw 87. In the free end of the lever 86 is a slot 88, and a pin 89 is fixed in the sliding bar 83 and operates in said slot 88, thus forming a pivotal sliding connection

between the lever 86 and the sliding bar 83. Upon the end of the lever 86, opposite the slot 88, is a handle 90 for manually operating said lever.

- 5 A sliding rod 91 is placed in the recess 40, and its rear end is pivotally connected to the handle end of the lever 86 by means of the bolt 92. Upon the front end of the rod 91 is a handle 93 for manually operating said rod.
- 10 By the construction just described the belt-shifter may be operated either from the front or left side of the machine, as desired.

The upper end 94 of the shaft 69 is screw-threaded and projects above the bearing in the plate 21, and the chopping-bowl 95 has a screw-threaded bore 96, formed vertically in its center and from its lower surface, and the screw-threaded end 94 of the shaft 69 is seated in said bore 96. Upon the bottom and in the center of the top of the bowl is a circular portion 97, which is flat upon its lower surface and rests upon the upper surface of the circular portion 68. When seen in cross-section, as in Fig. 2, the portions 98, which project outwardly and upwardly from the portion 97 of the bowl, are segments of a circle, and all parts of the bowl are circular when seen in plan. The segments of the inner surfaces of the portions 98 intersect each other exactly in the center of the bowl, thus forming the conical elevation 99. The weight of the bowl and all the parts attached thereto is supported by the plate 21, and the bowl is rotated by the operation of the worm 51, operating the worm-gear 70.

Mounted upon the left-hand rear corner of the plate 21 is a post 100, having the ear 101 projecting forwardly from its lower end and an ear 102 projecting toward the right from its lower end, and said post 100 is held securely in position upon said plate 21 by means of the lag-screws 103, inserted through said ears and into said plate.

The posts 104 and 105 are mounted in a line upon the plate 21 and in front of said post 100, and each of said posts 104 and 105 have ears 106 projecting, one forwardly and one backwardly, from the lower ends of said posts, and said posts are held in position upon said plate by means of the lag-screws 107, inserted through said ears and into said plate. The upper ends 108 of the posts 100, 104, and 105 are turned, and horizontal apertures are formed through said turned ends, near the upper ends thereof, and from left to right in horizontal positions to receive the spring-cotter 109, which spring-cotter are attached to the chains 110, and said chains are in turn attached to their respective posts, as shown in Fig. 3. Upon the right-hand rear corner of the plate 21 is mounted a post 111, which is identical with the post 100, with the exception that instead of the turned upper end the upper end 112 of said post 111 is transversely bifurcated, and a circular aperture is formed horizontally through said bifurcated portion from front to rear. The ear 113 extends for-

wardly from the lower end of said post 111, and the ear 114 extends toward the left from the lower end of said post, and said post is held in position by means of the lag-screws 115, inserted through said ear and into said plate 21.

The post 116 (shown in Fig. 2) is mounted upon the plate 21 in transverse alinement with the post 104 and in front of the post 111. The post 116 is attached to the plate in the same manner as the post 104 is attached, and its upper end is bifurcated and apertured in the same manner as the upper end of the post 111.

The post 117 (partially shown in Fig. 1 and also in Fig. 5) is mounted upon the plate 21 in transverse alinement with the post 105 and in longitudinal alinement with the posts 111 and 116. The post 117 is identical in construction with the post 116.

A post 118 is mounted in the center of the rear side of the plate 21 and in transverse alinement with the posts 111 and 100. An ear 119 (shown in dotted lines in Fig. 4) projects inwardly from the lower end of the post 118, and a lag-screw 120 is inserted through said ear and screw-seated in said plate 21, thus holding said post 118 securely in position. The upper end 121 of the post 118 is transversely bifurcated, and a horizontal aperture is formed from front to rear through said bifurcated portion to receive the spring-cotter 122, and said spring-cotter is attached to the chain 123, which chain is in turn attached to the post 118, as shown in Fig. 4.

The hinge-plate 124 (shown in plan in Fig. 1) is mounted above the posts, which are attached to the base-plate 21 in the following manner: Perforated ears 125 project downwardly from the lower face of the plate 124, and said ears are positioned between the bifurcated portions of the posts 111, 116, and 117, and pins 126 are inserted through said bifurcated portions of said posts and through said perforated ears, thus forming a pivotal and hinge connection between the plate 124 and the base of the machine. A perforated ear 127 projects downwardly from the rear edge of the hinge-plate 124 and between the bifurcated portions of the post 118, and the spring-cotter 122 is inserted through said bifurcated portion of said post 118 and through the perforation in said ear. In the left-hand side of the plate 124 are formed vertical apertures, through which the turned portions of the posts 100, 104, and 105, respectively, are inserted. After the plate has been positioned upon said turned portions and the spring-cotter are inserted through said turned portions the plate is held securely in position. The plate 124 covers the larger portion of the bowl 95, and when it is desired to gain free access to said bowl the spring-cotter 109 and 122 are removed from their respective apertures, and the plate 124 may be readily turned upwardly from the left side of the machine, as indicated in dotted lines in Fig. 2.

The plate 124 consists of the central portion 128, the rear portion 129, and the front portion 130, which portions extend entirely across the machine, as shown in Fig. 1. Between the central portion 128 and the rear portion 129 is a long narrow opening 131, which extends nearly across the machine, and the ends of the portions 128 and 129 are connected by the bars 132 and 133. Between the central portion 129 and the front portion 130 is an opening 134 similar to the opening 131, and the ends of said portions 128 and 130 are connected by the portions 135 and 136 in such a way that the lower surface of the portions 135 and 136 are on a plane with the upper surface of the portions 128 and 130.

Beads 137 project upwardly from all the edges of the hinge-plate 124 and connect with each other, thus forming basins, which basins will hold any oil, dirt, or other matter which may fall upon the plate 124 and prevent said oil and dirt from passing into the chopping-bowl.

Upon the rear portion 129 of the plate 124 are formed elevations 138 and 139, which elevations form the lower parts of the split bearings 140 and 141, respectively. Upon the front piece 130 of the plate 124 are formed elevations 142 and 143 in longitudinal alinement, respectively, with the elevations 138 and 139, which elevations form the lower part of the split bearings 144 and 145, respectively. Projecting upwardly from near the left-hand end of the rear piece 129 is a post 146, in which is formed a bearing for the stub-shaft 147.

The front portion 130 of the plate 124 is wider at its ends than at the points intermediate of its ends for the purpose of allowing as large an opening as possible into the front side of the bowl without elevating the plate. The parts composing the plate 124, as described, are all cast integral.

Shafts 148 and 149 are mounted in parallel positions, and said shafts are held in position relative to their respective bearings by means of the caps 150, composing the upper parts of said bearings, which caps are held in position by means of the lag-screws 151, as shown in Fig. 1. A balance-wheel 152 is mounted upon the shaft 148 and within the opening 131, and a similar balance-wheel 153 is mounted upon the shaft 149 within the opening 131, said balance-wheels being mounted out of alinement, so that their rims may overlap each other, as shown in Fig. 1. A belt-wheel 154 is loosely mounted upon the rear end of the stub-shaft 147 and in alinement with the belt-wheel 56 and serves as an idler. A belt-wheel 155 is rigidly fixed upon the rear end of the shaft 148, and a similar belt-wheel 156 is rigidly fixed upon the rear end of the shaft 149. The belt-wheels 155 and 156 are in alinement with the idler 154 and the belt-wheel 56, and a belt 157 is placed upon the belt-wheel 56 and passes upwardly to the left of the idler 154 and over said idler, thence over the belt-wheel 56 and down upon the right-hand side of said belt-

wheel and under said belt-wheel, thence to the left over the belt-wheel 155 and down upon the left-hand side of said belt-wheel, as required to drive the shafts 148 and 149 in opposite directions by the operation of the belt-wheel 56. Oil-boxes 158 are attached to the bearings of the shafts 148 and 149. A driving-belt 159 connects the source of motive power with the belt-wheel 57 and drives the machine. The portions 160 of the shafts 148 and 149 above the opening 134 are enlarged and screw-threaded, as shown in Figs. 9 and 10. Pairs of notches 161, 162, and 163 are cut in said screw-threaded portions, and the faces formed by each of the notches composing a pair are parallel with each other. The corresponding faces of the different pairs of notches are formed at angles of one hundred and twenty degrees relative to each other, as indicated in Fig. 11. Each of the knives 164 has a slot 165 in its head, and the arms formed by said slot are inserted in the notches 161, 162, or 163, as the case may be, as shown in Fig. 8. Nuts 166 are placed upon the screw-threaded portion 160 of the shaft, there being a nut upon each side of each knife, as shown in Fig. 9. Slots 167 are formed in opposite sides of the nuts, as shown in Fig. 2, and are designed to be engaged by a spanner for operating said nuts. Thus it will be seen that the knives are held from rotation upon the shaft by reason of their being inserted in the slots 161, 162, or 163, as the case may be, and that they may be adjusted laterally upon the shaft by the manipulation of the nuts 166 and that the points of the knives may be adjusted to and from the shaft by loosening the corresponding nuts and sliding the arms formed by said slots 165 in the required direction and then tightening the nuts again. The knives carried by the different shafts operate upon opposite sides of the cone 99 in the bowl, as shown in Fig. 2, and the points of the knives may be adjusted to cut as close to the inner surface of the portions 98 of the bowl as may be desired, and said inner surface is in a position concentric to the axis of the knives which operate against said surface. The brushes 168 and 168^a are placed against the upper surface of the portions 135 and 136, respectively, of the hinge-plate 124, as shown in Fig. 3. In the center of each of the portions 135 and 136 are formed vertical slots 169 and 170, which slots extend in a direction transversely of the machine, and the thumb-screws 171 and 172 are inserted through the slots 169 and 170, respectively, and are screw-seated in the brushes 168 and 168^a, respectively, as shown in Fig. 2. The fingers 173 of the brushes extend inwardly over the bowl, and the knives operate between said fingers, as shown in Figs. 1 and 9. Upon the outer ends of the brushes are handles 174 for operating the same when it is desired to remove and clean the brushes.

The slots 169 and 170 provide for the lateral adjustment of the brushes as required to bring the inner ends of the fingers 173 to

the desired position relative to the respective shafts.

A scraper 175 is attached to the left-hand end of the portion 130 of the hinge-plate 124 and extends downwardly into the chopping-bowl, as shown in Figs. 5 and 6. The scraper 175 is formed of a piece of sheet metal and is attached to the under side of the plates by means of the rivets 176, and the scraping edge 177 conforms closely to the shape of the bowl and is designed to throw the meat which is being chopped constantly toward the center of the bowl as the bowl is rotated under the scraper.

15 A scraper 178, corresponding in every essential to the scraper 175, is attached to the front and right-hand corner of the portion 128 of the hinge-plate 124 and extends downwardly into the bowl, as shown in Figs. 5 and 20 6, and upon the opposite side of said bowl from the first-mentioned scraper.

A sheet-metal cap 179 is placed over the knives and is removably held in position by means of the thumb-screws 171 and 172. The 25 cap 179 consists of the side pieces 180 and 181, which are substantially alike and of the shape shown in elevation in Fig. 2, and said side pieces are connected by the top piece 182, which extends from side to side of the 30 machine and has slotted apertures in its ends through which the thumb-screws 169 and 170 operate. The lower edges of the side pieces 180 and 181 have the slots 183 designed to receive the shafts 148 and 149, as shown in Fig. 5.

35 Otherwise said lower edges rest directly upon the hinge-plate 124.

I claim—

1. In a meat-cutting machine, the base 20 consisting of the rear piece 22 having a web 40 36 projecting inwardly in a horizontal plane, said web 36 being shorter than said rear piece 22, the front piece 23 having a web 36 projecting inwardly in a horizontal plane, said web 36 being shorter than said front piece, and the side pieces 24 and 25 connecting said rear and front pieces, the ends of said side pieces engaging the inner faces of said front and rear pieces and the inner faces of said side pieces engaging the ends of said webs, substantially as specified.

2. In a meat-cutting machine, the base 20; said base consisting of the rear piece 22 having a web 36 projecting inwardly in a horizontal plane, said web 36 being shorter than said rear piece 22, the front piece 23 having a web 36 projecting inwardly in a horizontal plane, said web 36 being shorter than said front piece, and the side pieces 24 and 25 connecting said rear and front pieces, the ends of said 55 side pieces engaging the inner faces of said front and rear pieces and the inner faces of said side pieces engaging the ends of said webs; the spider 58, having the circular portion 60 at its center, mounted in a horizontal 60 position in said base and having its arms attached to said webs 36, substantially as specified.

3. In a meat-cutting machine, the base 20; said base consisting of the rear piece 22 having a web 36 projecting inwardly in a horizontal 70 plane, said web 36 being shorter than said rear piece 22, the front piece 23 having a web 36 projecting inwardly in a horizontal plane, said web 36 being shorter than said front piece, and the side pieces 24 and 25 connecting said rear and front pieces, the ends of said side pieces engaging the inner faces of said front and rear pieces and the inner faces of said side pieces engaging the ends of said webs; the spider 58 having the circular portion 75 60 at its center, mounted in a horizontal position in said base and having its arms attached to said webs 36, the base-plate 21 mounted above said spider and resting upon the upper edges of the rear piece 22, the front 80 piece 23 and the side pieces 24 and 25, the ears 75 projecting downwardly from said base-plate inside of said side piece 24 and secured to said side piece by means of bolts, the ears 77 projecting downwardly from said plate inside of the side piece 25 and secured to said side piece by bolts, a shaft mounted in vertically-aligned bearings through said circular portion 60 of the spider and through said base-plate 21 and having a screw-threaded upper 90 95 end, a chopping-bowl having a screw-threaded bore in its center and formed from its lower side in which bore the screw-threaded end of said shaft is screw-seated, said bowl resting upon said base-plate, and means of rotating 100 said shaft, substantially as specified.

4. In a meat-cutting machine, the hinged plate 124 having the openings 131 and 134 extending transversely of the machine and near the ends of said plate, the shafts 148 and 149 105 mounted upon said plate transversely of said openings, balance-wheels upon said shafts and operating in said opening 131, chopping-knives mounted upon said shafts and operating in said opening 134, and means for operating said shafts, substantially as specified.

5. In a meat-cutting machine, the hinged plate 124 having the openings 131 and 134 extending transversely of the machine and near the ends of said plate, the shafts 148 and 149 110 115 mounted upon said plate transversely of said openings, balance-wheels upon said shafts and operating in said opening 131, chopping-knives mounted upon said shafts and operating in said opening 134, means of operating 120 said shafts, the brushes 167 and 168 adjustably attached to said hinged plate and extending into said opening 134, the scrapers 175 and 178 attached to and depending downwardly from said hinged plate, and the sheet-metal 125 cap 179 removably attached to said hinged plate and covering said opening 134, substantially as specified.

In testimony whereof I affix my signature in presence of two witnesses.

CHRISTIAN W. HINRICHES.

Witnesses:

EDWARD E. LONGAN,
MAUD GRIFFIN.
